UNITED STATES PATENT OFFICE.

WILLIAM B. PRINCE, OF CLEVELAND, OHIO, ASSIGNOR TO THE BISHOP-BABCOCK-BECKER COMPANY, OF CLEVELAND, OHIO, A CORPORATION OF OHIO.

ATTACHMENT FOR GAS-DRUMS.

1,293,917.

Specification of Letters Patent. Patented Feb. 11, 1919.

Application filed April 18, 1918. Serial No. 229,400.

To all whom it may concern:

Be it known that I, WILLIAM B. PRINCE, a citizen of the United States, and a resident of Cleveland, county of Cuyahoga, and State 5 of Ohio, have invented a new and useful Improvement in Attachments for Gas-Drums, of which the following is a specification, the principle of the invention being herein explained and the best mode in which I have 10 contemplated applying that principle, so as to distinguish it from other inventions.

The present invention, relating, as indicated, to an attachment for the regulating valve for gas drums, is more particularly 15 directed to the provision of a simple and inexpensive means for preventing the freezing of the regulating valve by the discharging gas, such means being preferably shown in the form of a casing partially inclosing the 20 valve and provided with means for heating the same. One object of the invention is the provision of a simple means for maintaining a uniform temperature at the regulating valve. To the accomplishment of the foregoing and related ends, said invention, then, 25 consists of the means hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 In said annexed drawing:—

Figure 1 is an elevation of a gas drum provided with a regulating valve and having heating means attached thereto; Fig. 2 is a similar view, but omitting the greater 40 part of the gas drum and showing the regulating valve partially inclosed in an open casing, to which the heating means is attached; Fig. 3 is a transverse vertical section through a modification of the device 45 shown in Fig. 2 and Fig. 4, and is a transverse vertical section of a further modified form of my device.

In Fig. 1 there is shown a gas drum 1, which is of the usual construction largely 50 used for holding nitrous oxide and other highly compressed gases for use in hospitals and other places. Attached laterally to the top of the gas drum is a conduit 2, which extends to a gas regulating valve shown as 55 inclosed in a substantially cylindrical cas-

ing 3 and operated by a hand wheel 4. The gas passes through this regulating valve and out through the conduit 5 and through a second controlling valve operated by a hand wheel 6. As the gas expands in passing 60 through the regulating valve, which is usually in the form of a diaphragm or disk provided with a small aperture therein, the effective size of which may be controlled by the hand wheel, the gas becomes very cold 65 as it gives up its heat in the expansion to that portion of the gas which passes through this opening. This decrease in the temperature of the gas freezes what moisture there is in the gas, of which there is always some, 70 and forms a film of snow on the diaphragm and around the edges of the valve opening, and in a very short time effectively closes this opening. If the regulating valve is 75 opened to its full extent the discharge of the gas therethrough will be intermittent, since after some gas has passed through the opening will be closed by the "freezing" of the opening, which then will have to thaw out before any other gas passes out. For this 80 reason, as stated, the discharging of the gas will be intermittent and will be interrupted every few minutes for a short time, due to the freezing or closing of the opening in the regulating valve. This is an ex- 85 tremely objectionable feature of such a device, as at the time when the gas may be needed most it suddenly ceases to flow and the regulating valve must be thawed out before any further discharge can be secured. 90 It is this objectionable feature the present invention is intended to overcome.

In Fig. 1 the cylindrical casing, which contains the regulator valve, is provided with a threaded boss 7 extending downwardly from its lower side for the attachment of a small heating lamp 8. This heating lamp may be of any suitable type and may be operated with alcohol or other fuel, and is provided with a framework consisting of rods 9, which carry an internally threaded nipple 10 engaging over the boss 7. The flame of the lamp is inclosed by a gauze cylinder 11 to prevent explosion or combustion of any gases that may be in the 105 atmosphere of the chamber in which the device may be in use. The operation of even such a small lamp as the one shown has been found to be sufficient to prevent any freezing in the regulating valve and to secure a 110

constant and steady flow of gas therethrough.

In Figs. 2 and 3 I have shown another type of heating means, which consists of an open casing 12 in the form of an uncovered box, which is provided at each of two opposite sides with hooks 13, which engage over the two opposite conduits 2 and 5 and maintain the boxes in a substantially horizontal position below and partially inclosing the valve casing 3. This casing 12 may be filled with water or any other suitable heating liquid to a sufficient depth to contact the casing 3, and a lamp 8, such as is shown in Fig. 1 may then be attached to a stud 14 disposed at the bottom of the casing 12. Such a device will cause an even closer regulation of the temperature of the valve casing 3 than is possible by the use of a lamp alone as shown in Fig. 1, since the outside conduction and convection of heat is very much more closely controlled.

In Fig. 4 I have shown a modification of the device of Figs. 2 and 3, and in this form a casing 15 will conform substantially to the shape of the regulating valve casing 3, being attached thereto by any suitable means, such as lugs, and will be spaced approximately a uniform distance therefrom at all points. This casing 15 is provided with a stud 17 at its bottom, to which a lamp 8 may be attached as in device already described. Instead of being formed as a part of, or attached to the valve casing 3 in the manner shown, this casing 13 may be mounted upon the conduits 2 and 5 by means of hoops similar to those used for forming the casing 11.

Other modes of applying the principle of my invention may be employed instead of the one explained, change being made as

regards the mechanism herein disclosed, provided the means stated by any of the following claims or the equivalent of such stated means be employed.

I therefore particularly point out and distinctly claim as my invention:—

1. The combination of a compressed gas regulating device, an open liquid containing casing attached thereto and inclosing the lower portion of said device, and a lamp attached to said casing and adapted to heat said casing and the liquid therein.

2. The combination of a compressed gas regulating device, provided with a threaded stud projecting downwardly therefrom, and a lamp adapted to be removably engaged on said stud and being also adapted to heat said device.

3. The combination of a cylindrical compressed gas regulating device, an open semi-cylindrical casing concentrically spaced from and partially inclosing the lower portion of said device, and a lamp attached to said casing and adapted to heat the same.

4. The combination of a cylindrical compressed gas regulating device having conduits extending laterally in opposite directions therefrom, an open semi-cylindrical casing provided with straps engaging over said conduits and supporting said casing concentrically and in a spaced relation to said device, and a lamp mounted on said casing and adapted to heat the same.

5. The combination of a compressed gas regulating device and a lamp adapted to be suspended adjacent said device and having a connection thereto, such connection being of heat-conducting material.

Signed by me this first day of April, 1918.

WILLIAM B. PRINCE.
